Wensan Wang, Setagaya-ku, Tokyo, Japan

Application April 24, 1956, Serial No. 41,185

Term of patent 14 years

(Cl. D85—8)

Figure 1 is a side elevational view of a reservoir type cigarette smoking pipe, showing my new design;

Figure 2 is a top plan view;

Figure 3 is a bottom plan view;

Figure 4 is a front elevational view; and

Figure 5 is a rear elevational view thereof.

A portion of the drawing figures is diagonally lined to indicate transparency.

The dominant features of my new design are shown in solid lines in the drawings.

I claim:

The ornamental design for a reservoir type cigarette smoking pipe, as shown and described.
